UNITED STATES PATENT OFFICE.

ELMER B. STONE, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

LOCK.

Application filed December 4, 1922. Serial No. 604,667.

To all whom it may concern:

Be it known that I, ELMER B. STONE, a citizen of the United States, and a resident of New Britain, in the county of Hartford 5 and State of Connecticut, have invented new and Improved Locks, of which the following is a specification.

My invention relates more especially to that class of locks known as cylinder or pin 10 tumbler locks, and an object of my invention, among others, is to provide effective means for preventing mutilation of the lock members, and especially such mutilation for the purpose of enabling the lock to be released, as to its locking members.

One form of lock embodying my invention and in the construction and use of which the objects herein set out, as well as others, 20 may be attained, is illustrated in the accompanying drawings, in which—

Figure 1 is a view in section through my improved lock shown as secured to a support, the plug being shown in full.

Figure 2 is a similar view, the plane of 25 section, however, being located at an angle of ninety degrees from the plane of view of Figure 1.

Figure 3 is a front view of my improved lock.

Figure 4 is a view in side elevation of my 30 improved lock shown as mounted in a support.

In the accompanying drawings the numeral 5 denotes a support, as a door or other structure to which the lock is secured, said lock comprising a cylinder 6, a plug or barrel 7 located within a plug socket in the cylinder and rotatable therein as by a key inserted into a key slot 8 to manipulate tumblers 9 and properly position them so that the plug or barrel may be turned, all of the parts thus far described being of old and well known form and the construction and operation of which will be, therefore, well 40 understood by those skilled in the art.

One method of tampering with a lock of this type, has heretofore embodied the operation of drilling into the lock structure from the face thereof and thereby mutilating the tumblers or other parts so that said tumblers would fail to perform their function and prevent rotation of the key plug or barrel. 50 With the lock thus mutilated the key plug or barrel may be turned by other means than the key fitted for such lock, enabling un-

authorized access to be had to the closure secured by such lock.

Several means have been devised for preventing the mutilation of such a lock to an extent to permit it to be operated, but such means have been directed toward the preventing of a drill or other cutting tool from gaining access to the tumblers or other parts of the lock.

I have provided means to not only prevent 65 a drill or other cutting tool from having access to the tumblers or other parts, but further to cause attempts to gain access to said tumblers to result in providing an additional means to secure the plug or barrel 70 against turning movement.

In the form of construction herein illustrated and described for securing these results I insert one or more barriers in the form of hardened metal plugs 10 in recesses 75 11 extending diagonally from the outer surface of the plug or barrel inwardly and lengthwise thereof, the mouths 12 of the recesses at the outer surface of the plug or barrel being closed by the inner wall of the 80 plug socket 13 in the cylinder 6. These barriers are placed in such positions as to intercept the movement of a drill or other cutting tool toward the locking members of the structure.

This arrangement is also of advantage as 85 an additional means for preventing rotation of the key plug or barrel. Should a hole be cut into one of the recesses 11 and the cutting tool encounter a barrier further cutting operation would be prevented. Should then an implement be inserted through the hole thus cut for the purpose of removing the barrier by driving the same, the latter would be 90 driven out of the mouth of its recess and wedged between the outer surface of the 95 said plug or barrel and the wall of the socket in which said plug or barrel is located, and this would serve to wedge such plug or barrel and prevent it from being rotated.

Similarly I also provide recesses 14 in the key cylinder 6, extending from the outer surface of said cylinder diagonally inward to a point at or near the surface of the plug or barrel 7, and I locate barriers 15, of hardened metal, within these recesses, such recesses and barriers being located in suitable 105 positions to intercept the movement of a drill or other cutting tool to vital parts of the lock structure, and as hereinbefore de- 110

scribed with respect to the plug or barrel. The operation and result of any attempt to move the barriers 15 will be the same as above described with respect to the barriers 10.

As another and additional means for preventing access to the vital parts of the lock I provide a barrier ring 16 surrounding the cylinder against a flange 17, this ring preventing any unauthorized attempt to drill into the structure to reach the vital parts thereof. Any of the barriers above described may be so arranged as to prevent the piece 18 that closes the holes for the tumblers from being reached.

The barriers are fitted within the recesses just tight enough to retain them in place by friction, but loose enough to enable them to be quite readily moved when force is applied to them in a longitudinal direction.

In accordance with the provisions of the patent statutes I have described the principles of operation of my invention, together with the device which I now consider to represent the best embodiment thereof; but I desire to have it understood that the device shown is only illustrative and that the invention may be carried out by other means within the scope of the appended claims.

I claim—

1. A lock including a member fitted within a smooth walled socket, and hardened means within said member to initially and solely prevent its movement by reason of a distortion and mutilation of the material of which the members comprising said lock is composed and a consequent displacement of said means from a normal, intended and inoperative position.

2. A lock including a member fitted within a socket and having a recess opening to its outer surface, and a hardened barrier located within said recess and arranged to mutilate the contact surface between said member and the wall of said socket when said barrier is forced from the normal, intended and inoperative position, and thereby initially and

solely prevent movement of said member in its socket by a distortion and mutilation of members comprising said lock.

3. A lock including a member fitted within a socket and having a smooth walled recess opening to its outer surface, and a hardened metal barrier held normally from movement in said recess and adapted to initially and solely obstruct movement of said member and the distortion and mutilation thereof by penetration of said smooth wall when said barrier is forced from its normal, intended and inoperative position.

4. A lock including a member fitted within a socket and having a diagonally arranged recess therein, and a hardened metal barrier located in said recess to engage the wall of said socket and prevent movement of said member when said barrier is forced from its normal, intended and inoperative position.

5. A lock including a cylinder fitted within a socket and having a diagonally arranged recess therein, and a hardened metal barrier located in said recess to engage the wall of said socket and prevent movement of said member when said barrier is forced from its normal, intended and inoperative position.

6. A lock including a plug or barrel fitted within a socket and having a diagonally arranged recess therein, and a hardened metal barrier located in said recess to engage the wall of said socket and prevent movement of said member when said barrier is forced from its normal, intended and inoperative position.

7. A lock including a cylinder member fitted within a socket, a plug or barrel member fitted within a socket in said cylinder member, both of said members having diagonally arranged recesses, and hardened metal barriers located in said recesses to engage the walls of said sockets and prevent movement of said members when said barriers are forced from normal, intended and inoperative position.

ELMER B. STONE.
